Primary Examiner — Sandra S Snapp*Assistant Examiner* — Ieisha N Price(74) *Attorney, Agent, or Firm* — Altera Law Group, LLC(57) **CLAIM**

The ornamental design for a wire manager, as shown and described.

DESCRIPTION

FIG. 1 is an environmental perspective view of a wire manger with a support pole and power cord disclaimed from the claimed design.

FIG. 2 is a perspective view thereof.

FIG. 3 is a top plan view thereof.

FIG. 4 is a bottom plan view thereof.

FIG. 5 is a right side elevation view thereof.

FIG. 6 is a left side elevation view thereof.

FIG. 7 is a front elevation view thereof; and,

FIG. 8 is a back elevation view thereof.

The features shown in broken lines depict environmental subject matter only and form no part of the claimed design.

1 Claim, 3 Drawing Sheets(56)
